(57) CLAIM

The ornamental design for a dress, as shown and described.

DESCRIPTION

FIG. 1 is front elevational view of an embodiment of a dress showing our new design;
FIG. 2 is a rear elevational view thereof;
FIG. 3 is a right side elevational view thereof;
FIG. 4 is a left side elevational view thereof;
FIG. 5 is a top plan view thereof;
FIG. 6 is a bottom plan view thereof;
FIG. 7 is front elevational view of a further embodiment of a dress showing our new design;
FIG. 8 is a rear elevational view thereof;
FIG. 9 is a right side elevational view thereof;
FIG. 10 is a left side elevational view thereof;
FIG. 11 is a top plan view thereof; and,
FIG. 12 is a bottom plan view thereof.

The broken lines are shown for the purpose of illustrating parts of the dress that form no part of the claimed design.

1 Claim, 8 Drawing Sheets
